UNITED STATES PATENT OFFICE

2,437,496

PHASING NETWORK

Nathan W. Aram, Chicago, Ill., assignor to Zenith Radio Corporation, Chicago, Ill., a corporation of Illinois

Application July 2, 1942, Serial No. 449,438

21 Claims. (Cl. 178—44)

1

This invention relates to phasing networks and particularly to networks which are arranged to supply power in proper phase relationship to a plurality of feeder lines.

A further object of the invention is to provide such a phasing network of coaxial lines of correctly matched impedances whereby equal power distribution of desired phase relationship among all of said plurality of lines is obtained.

A further object of the invention is to provide such a network adapted for the correct distribution of power of varying frequency in which the networks inherently provide compensation for variation of impedances of radiating elements with variation of frequency.

A further object of the invention is to provide a coaxial line network for equally distributing power from two main feeder coaxial lines to eight feeder coaxial lines in desired relative phase relationship.

A further object of the invention is to provide a coaxial line network for equally distributing power in desired phase relation from two main feeder lines to four pairs of feeder coaxial lines, the four pairs being arranged in symmetrical relation, each pair being opposite another pair, each main feeder line being connected directly to one of opposite pairs and by other coaxial lines to the other of such pair and to the lines of another pair.

A further object of the invention is to provide a coaxial line network for equally distributing power in desired phase relation from one or two main feeder lines to four pairs of feeder coaxial lines, the four pairs being arranged in symmetrical relation, each pair being opposite another pair, the main feeder lines being connected to lines of adjacent pairs and each being connected by other coaxial lines to the other of such pair and to the lines of another pair.

Other objects, advantages and capabilities will appear from the following description of a preferred embodiment thereof taken in conjunction with the accompanying drawings, in which:

Figure 1 is a wiring diagram of one embodiment of my invention;

Fig. 2 is a wiring diagram of a further embodiment of my invention; and

Fig. 3 is a wiring diagram of a still further embodiment of my invention.

In my application Serial No. 449,437, filed July 2, 1942, now Patent 2,338,564, I have disclosed an improved turnstile antenna which employs eight vertical coaxial feeder lines for the supply of energy in proper phase to radiating elements.

2

These vertical feeder lines are arranged in pairs around a mast which carries the radiating elements. Two of these vertical coaxial lines supply the north, for example, radiating elements, two others the south radiating elements, two others the east radiating elements, and two others the west radiating elements. It will, of course, be understood that the principal points of the compass have been selected merely for the purpose of ease of reference. While my improved phasing network is well adapted for employment with such a turnstile antenna, it will be understood that the invention is not intended to be limited to that purpose since it may be used in connection with other apparatus in which it is desired to distribute energy in desired phase relationship.

Referring to Fig. 1, the reference numerals 10, 11, 12, 13, 14, 15, 16 and 17 represent points on the vertical feeder lines of the application referred to, which points, for convenience, are referred to by the same numbers, on a reference plane, which may be a suitable plane below the radiating elements.

For the antenna disclosed in the application referred to, the points 16 and 12 are fed in opposite phase. The points 17 and 13 must lag the phase of 16 and 12, respectively, by 180 degrees. The phasing of the points 10, 11, 14 and 15 must be similar relatively to that of points 16, 17, 12 and 13, but between these two groups there must exist phase quadrature. In other words, one group must lead the other group by ninety degrees. In this embodiment, the former group 10, 11, 14 and 15, is arranged to lag the latter group 16, 17, 12 and 13.

Two balanced coaxial main feeder lines 18 and 19 are connected through quarter wave length transformers 20 and 21 to the points 16 and 12, respectively. The points 16 and 17 and the points 12 and 13 are connected respectively by means of half wave loops 22 and 23, respectively, which loops are also coaxial lines. The points 16 and 12 are connected by quarter wave loops 24 and 25 to the two points 14 and 10, respectively. The two points 14 and 10, respectively, are connected by half wave loops 26 and 27 to the points 15 and 11, respectively. The loops 24, 25, 26 and 27 are also preferably coaxial lines.

It will of course be understood that various changes may be made without deviating from the spirit of the invention. Thus, the loops 24 and 25 may be connected to the points 15 and 11 instead of the points 14 and 10. As fully explained in the application referred to, this change makes

no difference in the essential operation of the antenna which that application discloses.

If the vertical coaxial lines 10, 11, 12, 13, 14, 15, 16 and 17 have individual surge impedances of 70 ohms, then the loops 22, 23, 26 and 27 should likewise have a surge impedance of 70 ohms. The loops 24 and 25 should have individual surge impedances of 35 ohms. The impedance of the quarter wave transformers 20 and 21 is arranged to match the impedances of the lines 18 and 19 to the parallel impedances across the ends of these transformers connected to the points 16 and 12. This can readily be done by varying the internal diameter of the inner conductor of the quarter wave coaxial lines which constitute the transformers 20 and 21. The surge impedance of a coaxial line is given by the formula

$$138 \log_{10} \frac{d_1}{d_2}$$

where d_1 is the inner diameter of the outer conductor and d_2 the outer diameter of the inner conductor of the coaxial line.

It will thus be seen that by merely varying d_2 , the quarter wave transformers 20 and 21 may be made to have the proper surge impedance for matching the lines 18 and 19 to the points 16 and 12. As is well known, the surge impedance of the transformers 20 and 21, respectively, should be the geometric mean between the surge impedance of the line 18 and the impedance at the point 16 on the one hand, and the surge impedance of the line 19 and the impedance at the point 12 on the other hand, for proper matching.

Since the lines 18 and 19 are balanced lines, it will be obvious that if the instantaneous phase angle at 16 is 0, the phase angle at 12 is π , these points being of opposite phase, and the phase angle at 17 is π and the phase angle at 13 is 0, these being again of opposite phase. If desired, the loops 22 and 23 may be any other odd number of half wave lengths and the same result is obtained. Owing to the quarter wave lengths of the loops 24 and 25, the corresponding instantaneous phase angles at 14 and 10 are

$$-\frac{\pi}{2} \text{ and } \frac{\pi}{2}$$

the phase of these two points being again opposite. Owing to the half wave loops 26 and 27, the corresponding instantaneous phase angles at the points 15 and 11 are

$$\frac{\pi}{2} \text{ and } -\frac{\pi}{2}$$

these points again being of opposite phase. Thus, the points 10, 11, 14 and 15 have phases which lag the phases at 16, 17, 12 and 13, respectively, by ninety degrees, and the requisite phase quadrature is obtained.

If the vertical lines 10, 11, 12, etc., are standard 70-ohm coaxial lines, and the loops 22, 23, 26 and 27 are 70-ohm coaxial lines, they match the impedances of the vertical lines. The coaxial lines 24 and 25, each being a 35-ohm coaxial line, match the impedances of the two coaxial lines which are connected in parallel across their ends. That is, one end of the line 24, for example, is connected at the point 14 to the parallel impedances of the two vertical lines 14 and 15 which have impedances of 70 ohms. The surge impedances of the main feeder lines 18 and 19 are correctly matched to the parallel impedances at the points 16 and 12 so that correct

impedance matching exists throughout the network.

Since the impedance of the line 24 is equal to the parallel impedances of the lines 16 and 17, equal power distribution between the pair of vertical lines 16 and 17 and the pair of vertical lines 14 and 15 is established. Furthermore, since the surge impedance of the line 26 and the impedance of the vertical coaxial line 14 are equal, equal distribution of power between the vertical lines 14 and 15 is established. Thus, equal distribution of power is established between all the vertical lines 10, 11, 12, 13, 14, 15, 16 and 17, and the desired phase relation is established as has before been described.

In some cases it has been found impracticable to connect the main feeder lines 18 and 19 to opposite vertical lines such as 16 and 12, but it has been found possible to connect the main feeder lines to vertical lines of two adjacent pairs such as 14 and 12. For this purpose, the modification shown in Fig. 2 is preferably followed. The main feeder line 19 is connected to the vertical feeder lines 10, 11, 12 and 13 with the aid of the loops 23, 25 and 27 in exactly the same manner as shown in Fig. 1. Consequently, similar reference numerals are employed in Fig. 2 and it is not necessary to discuss the connections between 10, 11, 12 and 13 on Fig. 2.

In Fig. 2 the main feeder lines are 18' and 19. I provide an extra length or loop 28 in the line 18' of one quarter wave length so that the terminals of the lines 18' and 19 which are connected to the transformers 20' and 21 are not of opposite phase. Thus, if the instantaneous phase angle at the terminal of line 18' is 0, the phase angle at the terminal of the line 19 is

$$-\frac{\pi}{2}$$

The corresponding instantaneous phase angles at the points 14 and 12, respectively, are

$$-\frac{\pi}{2} \text{ and } \pi$$

respectively. It will be obvious that the corresponding instantaneous phases at the points 10, 11, 12 and 13 are the same as that given in the description of the preceding embodiment.

In the embodiment of Fig. 2, points 14 and 15 are connected by a half wave loop 26' and the points 16 and 17 are connected by a half wave loop 22'. Likewise, the points 14 and 16 are connected by a three quarter wave length line 24'. When the instantaneous phase angle of the point 14 is

$$-\frac{\pi}{2}$$

the phase angle at the point 15 is

$$\frac{\pi}{2}$$

Likewise, the corresponding instantaneous phase angle at the point 16 is 0 and the corresponding instantaneous phase angle at the point 17 is π . Thus, it is to be noted that I have established the same instantaneous phasing in the embodiments of both Fig. 1 and Fig. 2.

In the embodiment of Fig. 2, the impedance of the 70-ohm line 15 is properly matched by a 70-ohm loop 26' and a similar 70-ohm loop 22' matches the 70-ohm vertical line 17. A 35-ohm line 24' matches the parallel impedances of the lines 14 and 15 to the similar parallel impedances of the lines 16 and 17. As in the previously

described embodiment, the quarter wave transformers 20' and 21 properly match the surge impedances of the lines 18' and 19 to the parallel impedances at the points 14 and 12 to which they are connected. Consequently, equal distribution of power in proper phase relationship is supplied to all the vertical lines 10, 11, 12, 13, 14, 15, 16 and 17.

It will, of course, be understood that any of the lines 28', 22', 27, 23, 24' and 25 may be increased in length by any whole number of wave lengths.

My improved networks are particularly suitable for wide band operation, as for television transmission. Such wide band operation presents a problem in the fact that the antenna impedance is not constant with frequency. This impedance variation consists largely of a reactance term which becomes the greater as the frequency varies farther off resonance.

The folded dipoles described in my copending application above referred to, provide one degree of compensation for this reactance term due to the fact that the terminal impedance of each dipole is a combination of a series-resonant impedance of the dipole and a parallel-resonant impedance of the folded arms which form quarter-wave short-circuited lines. Since series and parallel resonant circuits have oppositely sloped reactance-frequency curves, the resulting impedance varies less with frequency than the series-resonant impedance or the parallel-resonant impedance alone. The off-resonant reactance of all the dipoles fed from points 14, for example (Fig. 1), add to a value equal to that at the points 16. Since the point 14 is connected to the point 16 by the quarter wave length 24, the reactance at point 14 is inverted at the end of the line 24 connected to the point 16, it is obvious that the variation of reactance at the point 14 is compensated by the variation of reactance at the point 16. A similar degree of compensation is also attained in the embodiment of Fig. 2 so that the main line transformer terminal impedance variation is the same as in the embodiment of Fig. 1.

In the embodiment of Fig. 2, a third degree of compensation is realized from the quarter wave length differential between the two lines 18' and 19 at their terminals, resulting from the quarter wave loop 28 in the line 18'. Whatever may be the value of the off-resonant reactance term at the terminals of the lines 18' and 19, this value, being equal for the two lines, appears at the transmitter end terminals with opposite signs for the two lines, because the quarter wave length loop 28 inverts the impedance of the line 19 at the terminal of the line 18'.

The two lines 18' and 19 are necessarily connected in series at the transmitter in order to obtain the necessary balance voltages at that point. The opposite reactance terms are compensating in the series connection and the line input impedance characteristic, as viewed from the transmitter, is thereby made more nearly constant with varying frequency.

The embodiment of Fig. 3 is similar to that of Fig. 2 with the exception that it is arranged for an unbalanced or single feed line 30. The point 14 is connected through a quarter wave transformer 29 to the single unbalanced coaxial feeder line 30, the connecting point being designated 31. The point 12 is connected to a quarter wave coaxial line transformer 32 similar to the quarter wave transformer 29. The quarter wave transformer 32 is connected at point 34 to a

quarter wave length coaxial line 33 which is connected to the point 31.

If the instantaneous phase at the point 31 is 0 then the instantaneous phases at the points 14 and 12 are

$$-\frac{\pi}{2} \text{ and } \pi$$

respectively, so that the same phasing is obtained as in the two previously described embodiments.

The two transformers 29 and 32 match the parallel impedances at the points 14 and 12, respectively, to double the impedance of the main feeder line 30. The line 33 has a surge impedance double that of the main feeder line 30.

The identical impedance against frequency characteristics measured at the points 14 and 12 appear at the point 31 with opposite phase angles and compensate in the parallel connection. The result is a more uniform impedance against frequency characteristic at the point 31 of the main feeder line 30, and therefore reflections are reduced in the main feeder line over a wider frequency band so that an improved line termination is attained. Consequently, my improved phasing network is well adapted for distributing power with frequencies within a relatively wide band.

Since the impedance of the line 30 is matched at the point 31 by two parallel impedances double the impedance of the line 30, it is obvious that equal distribution of power is attained at all the points 10, 11, 12, 13, 14, 15, 16 and 17.

Although the invention has been described in connection with specific details of a preferred embodiment thereof, it must be understood that such details are not intended to be limitative of the invention except in so far as set forth in the accompanying claims.

I claim:

1. A phasing network for feeding a pair of lines in opposite phases and another pair of lines in opposite phases and in phase quadrature to the first said pair, comprising a main feeder line connected to one of a pair of lines at a point of connection, a line of an odd number of half wave lengths connecting said point of connection to the other of said pair, a line of an odd number of quarter wave lengths connecting said point of connection to one of the other pair of lines, and a line of an odd number of half wave lengths connecting last said line to the other line of last said pair.

2. A phasing network for feeding a pair of lines in opposite phases and another pair of lines in opposite phases and in phase quadrature to the first said pair, comprising a main feeder coaxial line connected to one of a pair of lines, to a quarter wave coaxial line and to a half wave coaxial line, said half wave coaxial line being connected to the other line of said pair, the quarter wave coaxial line being connected to one of the other pair of lines and to a half wave coaxial line, last said half wave coaxial line being connected to the other of last said pair of lines.

3. A phasing network comprising four coaxial lines, a main coaxial feeder line connected to one of first said coaxial lines, a coaxial line of an odd number of quarter wave lengths connecting said main feeder line to a second of said coaxial lines, and coaxial lines of an odd number of half wave lengths connecting the first of said coaxial lines to a third of said coaxial lines and the second of said coaxial lines to a fourth of said coaxial lines.

4. A phasing network comprising four coaxial

lines, a main coaxial feeder line connected to one of first said coaxial lines, a coaxial line of an odd number of quarter wave lengths connecting said main feeder line to a second of said coaxial lines, and coaxial lines of an odd number of half wave lengths connecting the first of said coaxial lines to a third of said coaxial lines and the second of said coaxial lines to a fourth of said coaxial lines, the surge impedances of the coaxial lines of an odd number of half wave lengths being equal to the surge impedances of each of the four coaxial lines and the surge impedance of the coaxial line of an odd number of quarter wave lengths being half the surge impedance of one of each of said four coaxial lines.

5. A phasing network comprising eight coaxial lines arranged in pairs in generally square pattern to constitute two pairs of opposite pairs of lines, two main feeder coaxial lines of opposite phase connected to two opposite lines, four coaxial lines of an odd number of half wave lengths connecting the lines of each pair together, and a coaxial line of an odd number of quarter wave lengths connecting one main feeder line to one of an adjacent pair of first said coaxial lines, and another coaxial line of an odd number of quarter wave lengths connecting the other main feeder line to the coaxial line of first said coaxial lines opposite last said one of an adjacent pair of first said coaxial lines.

6. A phasing network comprising eight coaxial lines arranged in pairs in generally square pattern to constitute two pairs of opposite pairs of lines, two main feeder coaxial lines of opposite phase connected to two opposite lines, four coaxial lines of an odd number of half wave lengths connecting the lines of each pair together, and a coaxial line of an odd number of quarter wave lengths connecting one main feeder line to one of an adjacent pair of first said coaxial lines, and another coaxial line of an odd number of quarter wave lengths connecting the other main feeder line to the coaxial line of first said coaxial lines opposite last said one of an adjacent pair of first said coaxial lines, the surge impedances of first said coaxial lines and said coaxial lines of an odd number of half wave lengths being equal and being double the surge impedance of each of the lines of an odd number of quarter wave lengths.

7. A phasing network comprising eight coaxial lines arranged in pairs in generally square pattern to constitute two pairs of opposite pairs of lines, two main feeder coaxial lines in phase quadrature, one of said main feeder lines being connected to one of a pair of feeder lines, the other main feeder line being connected to one of an adjacent pair of feeder lines, two coaxial lines connecting said main feeder lines to ones of the other adjacent pairs, last said coaxial lines being of an odd number of quarter wave lengths and differing by an even number of quarter wave lengths, and four coaxial lines of an odd number of half wave lengths connecting each pair of lines together.

8. A phasing network comprising eight coaxial lines arranged in pairs in generally square pattern to constitute two pairs of opposite pairs of lines, a main feeder coaxial line connected to one of a first pair of feeder lines, a quarter wave coaxial line connecting said feeder line to one of a second adjacent pair of feeder lines, a second main feeder coaxial line connected to one of a third pair of feeder lines adjacent the first pair and opposite the second pair, said second main feeder line being adapted to lead in phase the

first main feeder line by ninety degrees, and a three-quarter wave coaxial line connecting second said main feeder line to one of the fourth pair of coaxial lines and four half wave coaxial lines connecting the feeder lines of each pair.

5. A phasing network comprising eight coaxial lines arranged in pairs in generally square pattern to constitute two pairs of opposite pairs of lines, a pair of unbalanced main feeder coaxial lines, a quarter wave loop in one line whereby said line is adapted to lead the other line in phase by ninety degrees, last said feeder line being connected to one of said pairs of coaxial lines, a three-quarter wave coaxial line connecting said feeder line to one of an adjacent pair of coaxial lines, the other main feeder coaxial line being connected to one of a pair of coaxial lines opposite last said pair, a quarter wave length coaxial line connecting last said feeder line to one of the other pair of coaxial lines, and four half wave coaxial lines connecting each pair of coaxial lines together.

10. In a phasing network having four feed points, in combination, a main feeder coaxial line connected to a first of said feed points, a coaxial line of an odd number of quarter wave lengths connecting last said feed point to a second of said feed points, and a coaxial line of an odd number of half wave lengths connecting first said feed point to a third of said feed points, and a coaxial line of an odd number of half wave lengths connecting the second of said feed points to the fourth of said feed points.

11. In a phasing network comprising eight coaxial lines arranged in pairs in generally square pattern to constitute two pairs of opposite pairs of lines, in combination, a main feeder line connected to one of a pair of said coaxial lines, a coaxial line of one quarter wave length connecting said main feeder line to a coaxial line of an adjacent pair, and a pair of half wave coaxial lines connecting the lines of each of two last said pairs together.

12. In a phasing network comprising coaxial lines arranged in pairs to constitute two pairs of opposite pairs of lines, in combination, a main feeder line comprising two conductors one of which is connected to one of a first pair of said coaxial lines, a quarter wave loop in said feeder line, the other one of said feeder line conductors being connected to one of a second pair of coaxial lines, a coaxial line of three quarter wave lengths connecting said one conductor of said main feeder line to a coaxial line of a third pair, three half wave coaxial lines each connecting individually the lines of each of said first, second and third pairs together, the lines constituting the fourth pair of said two pairs of opposite pairs of lines being connected together through a fourth half wave line, and a quarter wave line connecting said fourth pair to said second pair.

13. A phasing network comprising four coaxial lines of equal surge impedance, a main coaxial feeder line, a quarter wave length coaxial line transformer connecting said main feeder line to one of said four coaxial lines at a point of connection, a coaxial line of an odd number of quarter wave lengths connecting said point of connection to a second of said coaxial lines, and coaxial lines of an odd number of half wave lengths connecting the first of said coaxial lines to a third of said coaxial lines and the second of said coaxial lines to a fourth of said coaxial lines, said lines of an odd number of half wave lengths having a surge impedance equal to that of first

said coaxial lines, said coaxial line of an odd number of quarter wave lengths having a surge impedance of half that of said coaxial lines, said transformer having a surge impedance to match the surge impedance of the main feeder line to the parallel impedances of the four coaxial lines.

14. A phasing network comprising eight coaxial lines arranged in pairs in generally square pattern to constitute two pairs of opposite pairs of lines, two main feeder coaxial lines of opposite phase, two quarter wave coaxial line transformers connecting said main feeder lines to two opposite lines of said eight coaxial lines at points of connection, four coaxial lines of an odd number of half wave lengths connecting the lines of each pair together, a coaxial line of an odd number of quarter wave lengths connecting one of said points of connection to one of an adjacent pair of first said coaxial lines, and another coaxial line of an odd number of quarter wave lengths connecting the other point of connection to the coaxial line of first said coaxial lines opposite last said one of an adjacent pair of first said coaxial lines, the surge impedances of first said coaxial lines and said coaxial lines of an odd number of half wave lengths being equal and being double the surge impedance of each of the lines of an odd number of quarter wave lengths, said coaxial line transformers having a surge impedance which matches the surge impedances of the main feeder lines to the parallel impedances of the two pairs of four coaxial lines.

15. A phasing network comprising eight coaxial lines arranged in pairs in generally square pattern to constitute two pairs of opposite pairs of lines, two main feeder coaxial lines in phase quadrature, quarter wave coaxial line transformers connecting said feeder lines each to one of adjacent pairs of first said coaxial lines, two coaxial lines connecting said main feeder lines to ones of the other adjacent pairs, last said coaxial lines being of an odd number of quarter wave lengths and differing by an even number of quarter wave lengths, and four coaxial lines of an odd number of half wave lengths connecting each pair of lines together, said eight coaxial lines and said four coaxial lines of an odd number of half wave lengths having the same surge impedance and said lines of an odd number of quarter wave lengths having half last said impedance, each of said transformers having a surge impedance which matches the surge impedance of the line to the parallel impedances of four of first said coaxial lines.

16. A phasing network comprising eight coaxial lines arranged in pairs in generally square pattern to constitute two pairs of opposite pairs of lines, a main feeder coaxial line, a quarter wave transformer connecting said line to one of said pairs of lines, a quarter wave coaxial line transformer and a quarter wave coaxial line loop connecting said main feeder line to one of an adjacent pair of first said coaxial lines, two coaxial lines connecting said transformers to ones of the other adjacent pairs, last said coaxial lines being of an odd number of quarter wave lengths and differing by an even number of quarter wave lengths, and four coaxial lines of an odd number of half wave lengths connecting each pair of lines together, said eight coaxial lines and the four coaxial lines of an odd number of half wave lengths having the same surge impedance, said two coaxial lines of an odd number of quarter wave lengths having half last said

impedance, said quarter wave loop having double the impedance of the main feeder coaxial line and each of said transformers having an impedance which matches the parallel impedance of four of first said coaxial lines to double the impedance of the main feeder line.

17. A phasing network comprising four coaxial lines of equal surge impedance, a main coaxial feeder line, a quarter wave length transformer connecting the termination of the main coaxial feeder line to one of first said lines, a similar transformer and a quarter wave coaxial line loop in series connecting said termination to another of first said coaxial lines, and a pair of coaxial lines of an odd member of quarter wave lengths connecting said transformers to the other two of said four coaxial lines.

18. A phasing network comprising four coaxial lines of equal surge impedance, a main coaxial feeder line, a quarter wave length transformer connecting the termination of the main coaxial feeder line to one of first said lines, a similar transformer and a quarter wave coaxial line loop in series connecting said termination to another of first said coaxial lines, and a pair of coaxial lines of an odd number of quarter wave lengths connecting said transformers to the other two of said four coaxial lines, last said pair of lines of an odd number of quarter wave lengths and first said four coaxial lines having equal surge impedances, said coaxial line loop having a surge impedance of double the surge impedance of the main coaxial feeder line, said transformers having an impedance which matches the parallel impedances at their point of connection to lines of the first said four coaxial lines to double the impedance of the main coaxial feeder line.

19. A phasing network comprising eight coaxial lines arranged in pairs in generally square pattern to constitute two pairs of opposite pairs of lines, a main feeder coaxial line, a coaxial line connecting the termination of said main feeder coaxial line to a first line of one pair of coaxial lines, a coaxial line longer than last said coaxial line by an odd number of quarter wave lengths connecting said termination to a second line of an adjacent pair of lines, a pair of coaxial lines of an odd number of quarter wave lengths and differing in length by an even number of quarter wave lengths connecting said first and second lines respectively to a third and fourth line of the other two pairs of coaxial lines, and four coaxial lines of an odd number of half wave lengths connecting the two lines of each pair of lines together.

20. A phasing network comprising eight coaxial lines arranged in pairs in generally square pattern to constitute two pairs of opposite pairs of lines, a main feeder coaxial line, a coaxial line connecting the termination of said main feeder coaxial line to a first line of one pair of coaxial lines, a coaxial line longer than last said coaxial line by an odd number of quarter wave lengths connecting said termination to a second line of an adjacent pair of lines, a pair of coaxial lines of an odd number of quarter wave lengths and differing in length by an even number of quarter wave lengths connecting said first and second lines respectively to a third and fourth line of the other two pairs of coaxial lines, and four coaxial lines of an odd number of half wave lengths connecting the two lines of each pair of lines together, the surge impedance of the lines of an odd number of half wave lengths and the surge impedance of said eight coaxial lines being equal, the surge impedance of said pair of lines of an

2,437,496

11

odd number of quarter wave lengths differing by an even number of quarter wave lengths being half that impedance, the coaxial lines connected to the termination of the main feeder coaxial line being arranged to match double the impedance of the main feeder coaxial line to the parallel impedances of four of first said coaxial lines.

21. A phasing network comprising four terminals; a main feeder connected to a first of said terminals, a line of an odd number of quarter waves connecting said first terminal to a second of said terminals, a line of an odd number of quarter wave lengths connecting said second of said terminals to a third of said terminals, and a line of an odd number of quarter wave lengths connecting said first terminal to a fourth of said terminals.
